UNITED STATES PATENT OFFICE.

CHARLES L. BOLL, OF EVANSVILLE, INDIANA.

PROTECTOR FOR MAIL-BOX LOCKS.

1,055,865.

Specification of Letters Patent. Patented Mar. 11, 1913.

Application filed May 21, 1912. Serial No. 698,730.

To all whom it may concern:

Be it known that I, CHARLES L. BOLL, a citizen of the United States, residing at Evansville, county of Vanderburg, and

5 State of Indiana, have invented certain new and useful Improvements in Protectors for Mail-Box Locks, of which the following is a specification.

This invention relates to protectors for 10 mail box locks.

In cold and wet weather, the lock of the ordinary street mail box frequently becomes frozen and the mail collector has difficulty and wastes considerable time in opening the 15 box.

20 My object is to provide an improved swinging protector constructed and attached to the box in a new manner which will be adapted to fall by gravity and so positioned that it will normally house the lock, but at the same time being adapted to be readily lifted by the mail collector and either held or fastened in raised position while the mail is being removed from the box.

25 I am aware that it has been proposed heretofore to provide a swinging gravity-actuated protector for the lock of a mail box and I do not broadly claim such a device, my invention consisting, first, in the 30 construction of the protector itself; second, in the use of a hood under which the protector is disposed when closed so that rain, sleet and snow cannot gain access to the protector or to the lock and; third, in a device adapted to coöperate with the protector when the latter is swung upwardly to hold it in that position while the mail is being taken from the box, or as long as may be desired, thus preventing accidental dropping 35 of the protector on the hand or arm of the collector or in any manner interfering with the removal of the mail.

The invention is set forth fully herein-after and the novel features are recited in 40 the appended claim.

In the accompanying drawings:—Figure 1 is a front view of a mail box equipped with the invention, dotted lines showing the 45 position of the protector when raised and hooked up; Fig. 2, an end elevation; Fig. 3, a section on line 3—3, Fig. 2; and Fig. 4, a detail perspective view of the protector.

A mail box of ordinary or standard type is shown at 1 as provided with the usual 50 letter-receiving slot or door 2 by which mail matter is deposited in the box. At the end

of the box is the usual drop door 3 hinged at 4; 5 is the hasp of the lock for securing the door 3. As thus far described, the mail box is of the ordinary type.

I provide on the end of the box a hood having a slanting top 6 and end walls 7. The hood may be attached to the box in any desired manner and it is arranged somewhat above the door 3. The protector 8 is closed at its 65 upper end 9 and its outer face 10, being preferably rounded at its lower end 11, and there provided with a cut-out or notched part 12 and an aperture 13. The protector also has end walls 14, but it is otherwise 70 hollow so that it will be adapted to house or receive the hasp 5 and the usual lock. The distance between the end walls 14 is such that the upper end of the protector is adapted to fit snugly, yet easily, in between 75 the ears 7 of the hood. A pivot rod or bolt 15 passing through perforations substantially at or near the outer edge of the hood, pivots the protector 8 to said hood, there being provided hinge parts 16 and 17, re- 80 spectively, on the hood and the protector.

In consequence of the disposition of the pivotal or hinge connections between the protector and the hood, when the protector is down, its upper end lies underneath the 85 hood, and parts of its end walls 14 are also disposed within the hood and next the ears 7. Preferably, the point of hinging of the protector to the hood is at the extreme corner of the protector and that of the hood, 90 but the protector might be pivoted to the ears 7 so that the outer face thereof would be disposed nearer to the mail box, that is, the hood might overhang the protector. Preferably, the end 9 is provided on the 95 protector, but owing to the disposition of the protector in relation to the hood, particularly if the hood was allowed to more or less overhang the protector, such end 9 might be dispensed with. The hood may be cast 100 on the mail box or made of sheet metal.

A suitable hook or catch 18 is provided on the end of the mail box at a point where it will be adapted to engage or be engaged with the aperture 13. Preferably, a short 105 chain with a hook on its end is provided for this purpose. Normally, the protector houses the lock and is itself protected by the hood from access of rain, sleet and snow, the sloping top 6 tending to shed the elements in question so that freezing of the hasp or lock is rendered impossible. The 110

mail collector inserts his fingers in the opening 12 and raises the protector, engaging it, if desired, with the device 18. On disengagement from the device 18, the protector 5 may be allowed to drop by gravity and will remain in that position until access to the mail box is again desired.

Having thus described my invention, what I claim as new and desire to secure 10 by Letters Patent, is:—

The combination with a mail box and its lock, of a hood composed of a sloping top and ends secured to the mail box above the

lock, and a protector having sides and an outer wall, the sides being hinged to the end 15 walls of the hood so that the upper ends of the sides will be housed within the hood when the protector is in position to house the lock.

In testimony whereof, I hereunto affix my 20 signature in presence of two witnesses.

CHARLES L. BOLL.
